UNITED STATES PATENT OFFICE.

AUGUSTUS C. SAXTON, OF BROOKLYN, ASSIGNOR TO GEORGE S. BRACHER
AND JOHN VAN GELDER, BOTH OF NEW YORK, N. Y.

METHOD OF AND MACHINE FOR FORMING OVER-EDGE STITCHING.

SPECIFICATION forming part of Letters Patent No. 358,574, dated March 1, 1887.

Application filed October 21, 1885. Serial No. 180,492. (No model.)

To all whom it may concern:

Be it known that I, AUGUSTUS C. SAXTON, a citizen of the United States, residing at Brooklyn, county of Kings, State of New York, have invented certain new and useful Improvements in Methods of and Machines for Forming Over-Edge Stitching, of which the following is a specification.

This invention relates to over-edge stitching, and covers certain new and unique mechanical devices, whereby this class of stitching may be rapidly performed, and a firmer and more secure stitch made by the employment of a single thread than has heretofore been done.

My improvements in sewing-machines relate to an improved method of forming over-edge stitches by means of a single-thread sewing-machine having an eye-pointed reciprocating needle, presser-foot, feeding device, and supporting-plate, whereby the goods are fed under the needle, and the needle caused to pierce the same near the edge in the ordinary manner.

The invention embraces a looper, which consists of an irregularly-shaped piece of metal that may perhaps be best designated as a "spirally-formed wire" having a bill-shaped point, so actuated and controlled by certain mechanical devices as to be under the combined actions of three full movements in different directions—viz., a rotation on its axis, a longitudinal movement on its axial line, and one of position rocking to and from the needle, by all of which its bill-shaped point is caused to take the thread from the front side of the needle at the under side of the goods, carry the loop upward in a helical direction over the edge of the goods while the needle is being withdrawn from the goods and bring the loop under the point of the needle when it is in its highest position, so that the needle in its descent passes through the loop, which is then left on the needle by the retrograde movements of the

looper—viz., its backward movement of position, its retrograde rotation on its axis, and its downward longitudinal movement, at the completion of which movements the point of the looper is in its lowest position under the goods to again take the thread from the needle. The

action of the looper is such as to twist the loop of thread as it is being carried around the edge of the goods from the under to the upper side, thereby making the stitch firmer and more secure, especially when employed to bind and hold a reed or cord on the edge of the goods. A tension-guide is provided in the plate of the machine to act on the loop to keep it taut when it is being carried over the edge of the goods by the looper, which, with the devices employed to actuate the looper, will be now fully described, reference being had to the accompanying drawings, in which—

Figure 1, Sheet 1, is a side elevation of a sewing-machine embodying my invention. Fig. 2, Sheet 1, is a horizontal section of the same on the line $x x$, Fig. 1. Fig. 3, Sheet 2, is an end view. Figs. 4, 5, and 6, Sheet 2, are an enlarged side elevation in section, front elevation, partly in section, and plan view, respectively, of the stitch-forming mechanism, with the looper over the goods. Figs. 7, 8, and 9, Sheet 2, are similar views with the looper under the goods. Figs. 10 and 11, Sheet 2, are enlarged views illustrating the formation of the stitch. Figs. 12 and 13, Sheet 3, represent two pieces of goods sewed together by means of my improvements; and Fig. 14, Sheet 3, shows a modification in the mechanism for operating the looper. Fig. 15, Sheet 4, is an enlarged elevation of the spiral looper.

The looper and its operating mechanism are shown applied to the single-thread machine, known as the "Willcox & Gibbs sewing-machine," which, being so well understood, both as regards its construction and mode of operation, it is unnecessary to here describe, the only material changes made being the substitution of my looper for the old one and the formation of the tension-guide in the supporting-plate.

The looper consists of a spiral wire, a , having a bill-shaped point, with a shoulder, a' , on the under side of it, and a notch, a'' , in the upper side for forming the loop in the thread, and an internal shoulder, a''' , for insuring the retention of the thread on the point as it is taken from the needle. It is secured in the top of a cylindrical plug, b , fitted in the tubu-

lar holder *c*, and is provided with a small roller, *b'*, which projects from its side, and works in the spiral slot *c'*, formed in the holder *c*. To impart rotary motion to said looper, 5 the lower part of the plug *b* may be provided with the deep slot *b'*, into which fits the long flat head *d* of the shaft *d'*, forming a part of or secured to the pinion *e*. This shaft *d'* has bearings in the juncture of the two pieces of 10 metal, which constitute the rocking block *f* by being secured together by the screws *f' f' f'*, and the tubular holder *c* is securely clamped in the upper end of the block, concentric with the shaft *d'*. The block *f* is held between the 15 ears *g g* on the base of the machine, and the shaft or pin *g'* passes through them and the lower end of the block, and constitutes the center on which the block is rocked, as hereinafter described, so as to impart to the looper 20 *a* a sidewise movement of position to properly manipulate the thread.

Now, it will be observed that when the pinion *e* is rotated in the direction indicated by the arrow in Fig. 7 the flat end *d* of the shaft 25 *d'* causes the plug *b*, with the looper *a*, to rotate with it, and as the roller *b'* is confined in the spiral slot *c'* of the holder *c* the plug and looper are at the same time raised and assume the position shown in Figs. 4, 5, and 6. A reverse movement of the pinion *e* imparts to 30 them a retrograde rotation and downward movement and causes them to assume the position shown in Figs. 7, 8, and 9.

The upper and lower ends of the spiral slot 35 *c'* finish into short straight slots, so that the plug *b* and looper *a* have no vertical movement for a short interval at the limits of their rotation—that is, when the looper is taking the thread from the needle *h*, as shown at Figs. 7, 40 8, and 9, and when the needle is taking the loop from the looper *a*, as shown at Figs. 4, 5, and 6.

Reciprocal rotary motion may be imparted 45 to the shaft *d* and a rocking motion to the block *f* by means of any suitable mechanism actuated from any suitable moving part of the machine. In the drawings such mechanism consists of the segmental gear *i*, pivoted on the vertical stud *i'*, secured in the base of the 50 machine, and receives its motion from the cam *j*, secured to the main shaft *l* by means of the roller *j'* on the end of the arm *l'*, projecting from the hub of the segmental gear *i*, and the block *f* is controlled and rocked on its center 55 *g'* by means of the cam *m*, into which fits the roller *m'* on the end of the bent link *n*, the other end of which is pivoted to the block *f*. The vertical link *n'*, pivoted in an ear in the base of the machine, supports and guides the 60 roller end of the link *n*.

Instead of the plug *b* being rotated by means of a sliding connection with the shaft *d'*, to which the pinion *e* is secured, as before described, said shaft *d'* may be secured to or form 65 a part of the plug *b*, and the space between the bearings of the shaft *d'*, in which the pinion *e* is located, be made sufficiently great to allow

of the longitudinal movement of the pinion *e* with the plug *b*, as shown in Fig. 14, the pinion *e* being then made long, so as to remain in 70 mesh with the segmental gear *i* as it moves up and down with the plug *b*.

The plate *o* has formed in it an opening, *o'*, sufficiently large for the looper to pass through, and shaped, as clearly shown in Figs. 10 and 75 11, to connect with the hole through which the needle passes. The curved rounded edge *o''* acts as a tension-guide to insure the proper formation of the stitch by the looper *a*, as hereinafter described. The presser-foot *q* is also 80 cut away to allow for the free action of the looper, as shown in Figs. 4, 5, and 6, and the feed *r* is shaped as shown at Fig. 2 and actuated in the ordinary manner.

The cams *j* and *m* are timed and set to work 85 with the other parts of the machine, to cause the looper to co-operate with the needle and feed, as follows: The article to be sewed, where shown in connection with the mechanism, is represented as a bat-sweat in the drawings, and consists of a strip of material, *s*, on the edge of which it is desired to secure the reed or cord *s'*. These are placed in position under the presser-foot *q*, so that the needle *h* will pierce the strip near its edge, and after 90 being properly threaded and the machine operated descend through the goods into the vertical groove *c'* in the tubular holder *c*. The looper *a* is now in its lowest position, and is rotated as soon as the needle commences its 95 upward course, so that its bill-shaped point takes the thread from the front of the needle, as shown at Figs. 7, 8, and 9, and carries it in a loop up through the opening *o'* of the plate *o*. During such carrying of the loop it is in 100 contact with the curved rounded edge *o''*, which acts as a guide to keep the loop taut, as shown at Fig. 11, until the looper attains such a position that the loop slips off the rounded end of the edge *o''*, and around the reed or cord *s'*, 105 or the edge of the goods being sewed, and the looper *a* eventually arrives at the position shown in Figs. 4, 5, 6, and 10, it having been moved forward by the rocking of the block *f*, so that its point is behind the needle *h*, and the loop is held open by means of the shoulder *a'* and the notch *a''* for the needle to pass 110 through it in its next descent. While the looper is completing its movement, as just described, the feed *r* moves the goods forward, 115 acting in conjunction with the tension-guide edge *o''* to maintain a uniform tension on the loop, as well as to place the goods in position for the formation of the succeeding stitch.

It will be observed that the looper in carrying the loop helically from the under to the upper side of the goods imparts to the same a twist, as clearly shown in the enlarged views. This twisting of the loop adds greatly to the security of the sewing. Said twist may occur 120 on the extreme edge, as shown, or in other parts of the stitch, according to the tension of the thread and the adjustment of the moving parts of the machine.

When the needle h has passed through the loop, Fig. 10, the retrograde movements of the looper take place, leaving the loop on the needle, the point of the looper arriving in its lowest position in time to again take the thread from the needle at the under side of the goods and form the next stitch, as before described.

As well as forming a binding over-edge stitch, my improvements are well adapted to be used to bind or sew two pieces of goods together with their edges butting. This is accomplished by placing the two pieces of goods, t and t' , together, one above the other, with their edges in line, as shown in the sectional view, Fig. 13, and sewing them together in the manner before described, after which they are separated and spread out, as shown in Fig. 12, with their edges abutting, being so held by the stitches. If the finish sides of the goods are on the outside when the two pieces are placed together and sewed, then the form of stitch exposed will be represented by the full lines, and if the finish sides are adjacent when sewed, then the dotted lines will represent the exposed stitching.

Having now described my invention, in specifying what I particularly claim I wish it understood that I do not confine myself to the particular construction of the mechanical devices employed, as shown, to impart the proper movements to the looper to cause it to co-operate with the other parts of my machine, as any devices adapted to this purpose will come within the scope of my invention.

What I claim, and desire to secure by Letters Patent, is—

1. The improved method of forming single-thread over-edge stitches, which consists in passing the thread through the goods in the form of a loop, taking this loop from the under side of the goods, twisting it, and passing it around the edge and over the upper side of the goods, and then passing a second loop of the same thread through this loop as the thread is passed through the goods in commencing the next stitch, substantially as set forth.

2. The combination, with an eye-pointed needle and its reciprocating mechanism, of a spirally-shaped looper carried by a holder in a pivoted frame, and mechanism, substantially as described, whereby the looper is actuated to rotate and take the thread from the needle at the under side of the goods, twist it and carry it over the edge of the goods and move toward the needle, and hold the loop of thread open for the needle to pass through it, as set forth.

3. The combination, with a reciprocating eye-pointed needle and spiral looper, in conjunction with mechanism by which it is rotated, moved longitudinally, and moved to and from the needle, so as to take the loop from the needle at the under side of the goods, carry it over the edge of the goods, and hold it in position for the needle to pass through it when forming the next stitch, of a tension-guide consisting of the part of the edge of the

hole in the plate of the machine, through which the looper passes, formed so as to catch the loop of thread and keep it taut while it is being carried over the edge of the goods by the looper, substantially as set forth.

4. In a sewing-machine, in combination, a reciprocating eye-pointed needle, a spiral looper, and mechanism for holding it, moving it longitudinally, and moving it to and from the needle by which it is operated, to take the thread from the needle, twist and carry it over the edge of the goods, a tension-guide formed by a part of the edge of the hole in the plate of the machine, through which the looper passes, to keep the loop or thread taut during its passage over the edge of the goods, and a feeding device for moving the goods forward and keeping the loop taut on the looper when the loop slips over the edge of the tension-guide, substantially as and for the purpose set forth.

5. In a sewing-machine, a spirally-formed looper, in combination with mechanical means constructed and operated substantially as described, whereby it receives three full movements in different directions—viz., a reciprocating rotary device by which it is rotated on its axis, a helical slot in its holding-bearing which imparts to it a longitudinal movement on its axial line, and a lateral bearing on its holding-frame, and reciprocating mechanism connected thereto, which imparts to it an oscillating or rocking movement, substantially as and for the purpose set forth.

6. The combination, with the reciprocating eye-pointed needle h , of the spiral looper a , having a shoulder, a' , on its under side near the point, the notch a'' on its upper side, and the internal shoulder, a''' , and mechanism for rotating the looper on its axis, moving it longitudinally, and oscillating it to and from the needle, substantially as and for the purpose set forth.

7. In combination, the spiral looper a , the plug b , having a slot, b^2 , and provided with the roller b' , the tubular holder c , provided with the spiral groove c' , and the shaft d , with the flat head d , and reciprocating rotary mechanism for actuating the shaft d , substantially as described.

8. In combination, the looper a , plug b , tubular holder c , shaft d , with pinion e , segmental gear i , and reciprocating or rocking holding-block f , substantially as and for the purpose set forth.

9. In combination, the cams j and m on the main shaft of a sewing-machine, segmental gear i , with arm i' , rocking on a stud from the base of the machine, pinion e on shaft d , held in the block f , the link n , the block f , held on the shaft or pin between the ears g g' , the spiral looper a , held in the block f and actuated by the shaft d , and the eye-pointed needle h , carried by a reciprocating bar actuated from the main shaft of the machine, substantially as and for the purpose set forth.

10. In combination, the spiral looper a ,

mechanism for imparting a rotary movement, a longitudinal movement, and an oscillating movement to the looper *a*, the plate *o*, with the tension-guide *o*², the needle *h*, mechanism for vertically reciprocating the needle, and a feeding device, *r*, and its operating mechanism, substantially as and for the purpose set forth.

11. In combination, the spiral looper *a*, mechanism for imparting a rotary movement, a longitudinal movement, and an oscillating movement to the looper *a*, the plate *o*, with the tension-guide *o*², the eye-pointed needle *h*, with its reciprocating mechanism, the feeding device *r*, with its operating mechanism, and the presser-foot *q*, substantially as and for the purpose set forth.

12. In combination, the spiral looper *a*, plug *b*, provided with roller *b*', to which plug the looper is attached, the tubular holder *c*, with the spiral groove *c*', having straight parts at its ends, and the longitudinal slot *c*², and the needle *h*, vertically reciprocated so as to enter the slot *c*², substantially as and for the purpose set forth.

In testimony whereof I have hereunto set my hand, at New York, county and State of New York, this 10th day of December, 1884.

AUGUSTUS C. SAXTON.
